REMOTELY PILOTED VEHICLE DRIVEN BY A PUSHER PROPELLER

Le Roy I. Sather, 2532 14th W., Seattle, Wash. 98119

Filed Aug. 25, 1971, Ser. No. 175,028

Term of patent 7 years

Int. Cl. D22—04

U.S. Cl. D22—11

FIG. 1

FIG. 2

FIG. 3

FIG. 4

FIG. 5

FIG. 6

FIG. 1 is a top plan view of a remotely piloted vehicle driven by a pusher propeller;

FIG. 2 is a front elevational view of said vehicle;

FIG. 3 is a bottom plan view of said vehicle;

FIG. 4 is a rear elevational view of said vehicle;

FIG. 5 is a side elevational view of one side of said vehicle; and

FIG. 6 is a side elevational view of the other side of said vehicle.

I claim:

The ornamental design of a remotely piloted vehicle driven by a pusher propeller, substantially as shown.
